Attorney.

UNITED STATES PATENT OFFICE.

THOMAS L. RANKIN, OF NEW YORK, N. Y., ASSIGNOR TO THE RANKIN ICE MANUFACTURING COMPANY, OF SAME PLACE.

REFRIGERATING-BUILDING.

SPECIFICATION forming part of Letters Patent No. 244,301, dated July 12, 1881.

Application filed May 5, 1881. (No model.)

To all whom it may concern:

Be it known that I, THOMAS L. RANKIN, of New York, in the county and State of New York, have invented certain new and useful 5 Improvements in Refrigerating-Buildings; and I do hereby declare that the following is a full, clear, and exact description thereof, reference being had to the accompanying drawings, and to the letters of reference marked thereon, 10 which form part of this specification.

The objects of this invention are to increase the efficiency of the metallic cooling-pipes employed to circulate a liquid or gas in a building for cooling the air therein, or in an ice-machine for congealing the water to be converted into ice, and, as a consequence of the increased efficiency of the pipes, to enable smaller pipes and a less quantity of the refrigerating liquid or gas to be used than heretofore in accomplishing the desired effect. 15 Incidentally to the accomplishment of these objects there also results an economy of construction of systems of cooling-pipes and a reduction of waste by leakage, as a less number of joints are necessary in making return-bends, and said joints are smaller.

My invention consists in the combination, with the metallic cooling-pipes, of metallic plates having extended surfaces and secured 30 to the pipes in contact therewith, whereby the plates are deprived of their heat and present an extended frosting or cooling surface to the air or water in contact therewith.

In the accompanying drawings, Figure 1 is 35 a vertical section of a house provided with a system of cooling-pipes according to my invention. Fig. 2 is a horizontal section of the house in a plane indicated by the line α , Fig. 1. Fig. 3 illustrates a modification of the cooling-plates. Fig. 4 shows another modification of the plates, and Fig. 5 illustrates a modification of the means of attaching the plates to the pipes.

Referring to Figs. 1 and 2, the letter A designates a series of parallel iron pipes connected by return-bends, and each end pipe of the series connected with a pipe, B, by which connection is made with the source of supply of the refrigerating liquid or gas. The series of

pipes is composed of two sections, each of 50 which is inclined downwardly to a point midway the chamber.

The letter C denotes the metallic cooling-plates, which in these two figures are oblong and rectangular in shape, there being a plate 55 for each straight parallel piece of the pipes of nearly equal length therewith. Each plate is arranged under and in contact with its pipe, and is secured thereto by straps D D D D, attached to its upper surface and passing around 60 the pipe. The plates of each section are inclined transversely downward to the center of the house, the edge of each plate overlapping the margin of the next lower, the inner edges of the two lowest plates terminating over a 65 trough, E, arranged to carry off the water of condensation which collects upon the plate-surfaces and flows downward. In this arrangement the economy in pipe and refrigerating material, and the increased efficiency of the 70 pipes over pipes without plates, will be apparent. As the pipes are cooled by the circulation of the refrigerating material within them, the plates are cooled by contact with the pipes, and there is a cooling-surface thus presented 75 to the air far in excess of that afforded by the pipes alone.

In Fig. 3, which represents a portion of a series of pipes with a modified form of plates, the plates C' are corrugated transversely, thus 80 presenting within given limits a greater surface than is afforded by the flat plates.

At the upper edge of the series of plates in Fig. 3 is arranged an overflow-trough, F, having the top of its front wall notched. In this 85 trough I cause to flow, by means of a suitable supply-pipe, a non-congealable brine, which trickles through the notches, falls upon the plates, and flows down over them successively. Such plates are to be arranged in downwardly- 90 converging sections, terminating over a trough, the same as in Figs. 1 and 2, the trough carrying off the brine as well as the water which is condensed from the air. The brine becomes cooled by the plates, absorbs and carries off 95 unwholesome vapors, and thus greatly promotes the purification of the air.

In lieu of the rectangular plates, metallic

disks C² may be arranged concentrically upon the pipes, as seen in Fig. 4. With this form of plates the series of pipes may be all arranged in the same plane, as the water of condensation will flow down the surfaces of the disks.

In the modification of the plates shown in Fig. 5, the separate attaching-straps are dispensed with, and through the plates are parallel slits at a suitable distance apart, the narrow portion of the plates between said slits being bent outward from the main portion to form straps D', under which the pipe A is passed.

While I have now described and shown my invention as applied to the cooling of air, it is obvious that the advantages derived therefrom would be the same were the plates placed in contact with water or any other liquid to be cooled or frozen.

What I claim is—

1. The combination, with a metal cooling-pipe employed for conveying a refrigerating liquid or gas, of one or more metallic plates having an extended surface, and secured to said pipe in contact therewith, substantially as described.

2. The combination, with a metal cooling-pipe employed to conduct a refrigerating liquid or gas, of a corrugated metallic plate secured broadside to said pipe, and in contact therewith, substantially as and for the purpose specified.

3. A system of metal cooling-pipes consisting of a series of lengths of pipe connected by bends, and each length provided with a metallic plate arranged below and in contact with it, substantially as described.

4. A system of cooling-pipes composed of a downwardly-oblique series of pipe-lengths, connected by return pipes or bends, and provided with underlying attached metallic plates arranged to shed water from one to another, substantially as described.

5. The combination, in a system of metal cooling-pipes, of the two downwardly-converging connected sections of parallel return-pipes, the lapping obliquely-arranged metallic plates connected to said pipes, and the trough arranged to receive the water shed from said plates, substantially as described.

6. The combination, with a downwardly-inclined series of metal pipes, side by side, and connected by return-bends, of a series of underlying metallic plates connected to said pipes and arranged to shed water from one to another, and of an overflow-trough arranged along the upper edge of said series of plates, substantially as and for the purpose set forth.

In testimony that I claim the foregoing as my own I affix my signature in presence of two witnesses.

THOMAS L. RANKIN.
